CLAIM

The ornamental design for a jump rope, as shown and described.

DESCRIPTION

FIG. 1 is a top, right side perspective view of the jump rope showing the design, the broken-line disclosure of a person using the jump rope is being shown for illustration purposes only and forming no part of the claimed design;

FIG. 2 is an top side perspective view of one of the handles of the jump rope, the other handle being identical, the rope being shown broken for ease of illustration;

FIG. 3 is a top plan view of one of the handles;

FIG. 4 is a bottom view of one of the handles;

FIG. 5 is a front elevational view of one of the handles;

FIG. 6 is a side elevational view of one of the handles; and,

FIG. 7 is a longitudinal cross-section view of one of the handles.

The words “Coca-Cola” forming part of the claimed design is a registered trademark of the Coca-Cola Company.
